UNITED STATES PATENT OFFICE.

ALBERT KRAUSE, OF BUFFALO, NEW YORK.

TUNNELING-SHIELD.

SPECIFICATION forming part of Letters Patent No. 326,659, dated September 22, 1885.

Application filed March 5, 1885. (No model.)

To all whom it may concern:

Be it known that I, ALBERT KRAUSE, of the city of Buffalo, in the county of Erie and State of New York, have invented new and useful Improvements in Tunneling-Shields, of which the following is a specification.

This invention relates to an improvement in that class of tubular metallic shields which are used in tunnelling through soft earth, sand, &c., 10 for supporting the roof of the bore or heading in front of the brick-work or arch. These shields are usually constructed with vertical front ends and forced into the earth by jack-screws or hydraulic presses applied to lugs or 15 brackets secured to the inner side of the shield and abutting against the brick-work. The upright front or entering end of the shield causes the earth to fall into and conceal the lower front portion of the shield, whereby the 20 lower front portion of the shield is rendered inaccessible to the workmen. When obstructions—such as bowlders, for instance—are encountered by the lower front portion of the shield, it is extremely difficult to remove them, 25 and the shield is often thereby deflected out of its true course. As the earth cannot be removed from before the lower front portion of the shield, the latter must be forced into the earth, which operation requires considerable force, and is very destructive to the shield.

The object of my invention is the construction of a shield which shall avoid these difficulties; and my invention consists, essentially, of a movable tubular shield constructed with 35 an overhanging front end, which is inclined substantially in accordance with the angle of repose of the material in which the shield is used, whereby the entire front end of the shield is rendered accessible, as will be hereinafter fully explained, and pointed out in the 40 claims.

In the accompanying drawings, Figure 1 is a longitudinal sectional elevation of my improved shield constructed for tunnels of small size. Fig. 2 is a perspective view thereof. Fig. 3 is a longitudinal section of my improved shield constructed for tunnels of large size. Fig. 4 is a cross-section in line $\alpha\alpha$, Fig. 3. Fig. 5 is a longitudinal section of the front 45 end of this shield on an enlarged scale.

Like letters of reference refer to like parts in the several figures.

A represents the body of the tubular shield, made of cylindrical, oval, or any other suitable tubular form which the cross-section of 55 the tunnel may require, and somewhat larger than the tunnel, as usual.

a represents the front or entering edge of the shield, which is inclined backwardly, in accordance with the angle of repose of the 60 material in which the shield is used, so that the material cannot enter the front end of the shield, said angle averaging from forty to fifty degrees in the loose soils in which tunneling-shields are usually employed. In small shields 65 the front edge, a, may be composed of a single continuous incline, as represented in Figs. 1 and 2; but in large shields it may be composed of two parallel inclines, a a', one below the other, as represented in Fig. 3, and even a 70 greater number of inclines may be employed, if desired. The two inclines a a' are separated by a horizontal platform, B, secured transversely in the front portion of the shield, and serving to stiffen the front end of the shield, 75 and affording a support for the workmen.

C represents a door or gate hinged to the under side of the platform B at the front end of the latter, and serving to close the front end of the shield below the platform B when it is 80 desired to exclude quicksands or other material from the shield. The door C is ordinarily fastened against the under side of the platform B by a turn-button, d, or other suitable catch, as represented in Fig. 5.

D is a brace hinged to the under side of the platform B, near the rear end of the latter, and serving to secure the door C when the latter is lowered, as represented in Fig. 3. In 85 this construction one workman can work on 90 the platform B and another below the same.

E represents an overhanging hood or top extension formed at the rear end of the shield to protect the front portion of the brick-work, and f represents the brackets or lugs, to which 95 the jack-screws F are applied in the usual manner.

The shield may be provided with longitudinal and transverse stiffening-pieces, as may be necessary. The front end of the shield being inclined in accordance with the angle of repose of the earth, sand, or other material in which the shield is used, the material cannot 100 enter the shield, and the entire front edge of

the shield from its crown to its bottom is accessible to the workmen, who can readily remove the earth from before the front edge all around the shield, thereby making room for the shield, so that the jack-screws or other pressing appliances are only required to move the shield into the space so formed for its reception, instead of being employed for pressing the shield into the earth. As the entire front edge is accessible, bowlders and other obstructions can be readily reached, and be removed or cut off, as may be required.

Tunneling-shields have a tendency to work upwardly, owing to the fact that the earth is compact below the front end of the shield and loose above the same, and this tendency is readily counteracted in my improved shield by removing the earth from under the front end of the shield, which portion of the shield is as readily accessible as the top portion. For the same reason, the sub-drain (represented at G in Fig. 3) can be laid under the front end of the shield, thereby removing the water from before the shield and preventing it from entering the shield, and bearing-pieces, composed of longitudinal timbers or twisted bundles of straw, can be laid under the front end of the shield, thereby facilitating the

movement of the shield and reducing the friction and the consequent wear, which is very severe and destructive when working in hard gritty material.

I claim as my invention—

1. A movable tubular tunneling-shield having its overhanging front end inclined substantially in accordance with the angle of repose of the material in which the shield is used, thereby preventing the material from entering the shield, and rendering its entire front edge accessible, substantially as set forth. 35

2. A tunneling-shield provided with inclined front edges, *a a'*, one above the other, and a horizontal platform, B, substantially as set forth. 40

3. The combination, with the tunneling-shield, of a platform, B, secured in the shield, and a pivoted door, C, adapted to close the space below the platform, substantially as set forth. 45

4. The combination, with the tunneling-shield, of a platform, B, hinged door C, and brace D, substantially as set forth. 50

Witness my hand this 26th day of February, 1885.

ALBERT KRAUSE.
